2 Claims. (Cl. 197—27)

1

Our present invention relates to improvements in a typewriter having an inclined segment for pivotably supporting and guiding the type-levers, and a conventional four-row keyboard.

It is an object of our invention to provide a machine of simple structure and positive and reliable operation by interlinking the key-levers with the type-levers without intermediate levers, and by so arranging the key-levers that their outswinging arms are bent off, i. e. out of their planes, and at an increasing rate from the vertical median plane of the machine toward the sides, in the direction of the type-lever bearing-slots. The rate of bending or angular deflection so depends upon the slope of the segment, the position of the type-lever bearing-slots, and upon the associated plane of swing of the key-lever that the outswinging ends of the latter move in the plane of their respective type-lever bearing-slots.

It is a further object of our invention to substantially simplify the spacing-mechanism by mounting the actuating rocker on the spacing bridge, and by adapting the said rocker so as to also actuate the ink-ribbon mechanism feed and lift.

A still further object of our invention is to substantially simplify the paper feed by pressing the paper guide—on which an engaging roller and a paper guiding roller are mounted—universally movably onto the platen by means of a spring which in the median plane and intermediate of the said cylinders engages the said guide. The latter is pivoted on two slides which are disposed slidably on the sidewalls of the carriage, and the said slides are adjustable against the action of said spring for the purpose of lifting the said guide off the platen.

It has proved difficult to attain—in a machine of the character outlined above—a light operating touch or tap in connection with a sufficient copying momentum and a high speed of writing.

In accord with our present invention, further, such latter difficulty shall be overcome by virtue of the following arrangement. Each key-lever is directly coupled to its appurtenant type-lever by means of a short link. When the keys are successively depressed, the links pivot points of the key-levers are situated on a spatial curve. A straight line in space, which passes through the points of intersection of the pairs of tangents—which are situated symmetrically to each other on the pivotal or coupling points of the depressed key-levers—includes with the plane of the segment a certain critical angle which may be analytically derived.

One form of our invention is shown in the accompanying drawings, in which—

Fig. 1 shows a top plan view,

2

Fig. 2 is a vertical cross-section,

Fig. 3 is a schematical top plan view of the type action,

Fig. 4 is a side view of Fig. 3,

Fig. 5 is a vertical section on line V—V of Fig. 3,

Fig. 6 is a perspective view of the escapement mechanism of the spacing-mechanism, including the rocker, the ink-ribbon mechanism and the ribbon vibrator, as seen from the paper carriage,

Fig. 7 is an elevation of the paper feeding and guiding arrangement,

Figs. 8—10 each show an end view of Fig. 7 in three different positions,

Fig. 11 shows a system of spatial co-ordinates, including planes of reference, and

Fig. 12 illustrates schematically the bearing-arrangement and disposition of the bar action.

As shown in Figs. 1—5, the key-levers 1 are supported, with a V-notch each, in open slot-bearings of a pedestal 2 which is secured to the bottom plate 3. The latter at the same time forms the machine frame, and tension springs 4 pull the key-levers 1 downward against their bearings. Each key-lever 1 is articulated to a type-lever 6 through a wire link 5. The type-levers 6 are guided in slots of the inclined stationary segment 7, as well known, and borne for rotation on a wire axle 8. The type-levers—from the centre of the segment toward both sides—are made of gradually increasing length, and the wire 8 correspondingly so curved that all the type-levers strike from their position of rest upward against a point situated in close proximity of the central guide 9. The type-lever axle 8 is inserted into the bearing-groove provided on the underside of segment 7, through the bores in the end portions of the aligned type-levers 6, and clamped down. In the present form of invention, the type-lever axle 8 is bent on a composite curve. The selection of the type-lever lengths substantially depends upon the arrangement of the conventional keyboard, upon the inclination of the shanks of the key-levers 1 relative to the vertical median plane of the machine (such inclination is illustrated in Fig. 5 by the bearing-slots of pedestal 2 as increasing in a direction toward the ends of the latter), and upon the angular bend of the key-levers 1 as seen in plan in Fig. 1, which bend also increases in a direction toward the ends of pedestal 2. Such inclination and bend allow the inner ends of the key-levers (which serve for actuating the type-levers) to swing in the planes of throw of their appurtenant type-levers. The different angles of bend of the key-levers thus depend upon the inclination of the type-lever bearing structure or segment 7, the position of the plane of the type-lever bearing-slot, and the

50
30
35
40
45
50
55

individual appurtenant position of the plane of swing of the key-levers in such degree that the swinging key-lever inner ends move in the planes of their respective type-lever bearing-slots.

Since the wire links 5 all are of equal length, the key-lever inner ends (which are gradually bent off in plan from the centre of the machine toward the two sides) also have to be gradually bent up in elevation in the direction from the centre of the machine toward the two sides in accord with the guiding-slots in the segment 7. At the same time, the length of the bent-off inner ends of the key-levers has to be gradually increased in the said direction. All the points of support of the key-levers 1 are situated in a horizontal plane (see Figs. 2 and 5), the position of which depends upon the slope of segment 7. The same holds true for the points of bend of the key-levers 1.

As seen from Figs. 1, 2 and 6, a bridge 11 is secured to the bottom plate 3 of the machine and supports the inclined segment 7 as well as an axle pin 14 on which the escapement ratchet wheel 13 (Fig. 2) and the pinion 12 fixed to the latter are rotatably mounted. The rocker 15 is pivoted on the pointed screws 16 to the side lugs of the bridge 11, and is held in a predetermined position by means of a spring 17 (Fig. 6). The universal bar 10 is guided, in a manner known, by means of a guide arm 18 so as to be movable in a plane. The said universal bar 10, by means of a pin 10' on each side, is pivoted in two side lugs of the rocker 15 so that the latter, by the action of a type-lever 6 on the universal bar 10, is rocked, thereby bringing the pawl 19, which is fixed to rocker 15, into engagement with the escapement wheel 13.

A toothed rack 20 (only shown in Figs. 1 and 2), secured to the paper carriage, is engaged by the pinion 12. The latter and the ratchet wheel 13 fixed thereto, tend to rotate clockwise by virtue of the unidirectional spring tension acting on the paper carriage. Owing to the cooperation of the movable pawl 22—which is biased by the spring 21 and mounted, through a pin-and-slot guiding-arrangement, on the front side of the rocker 15—and the pawl 19 which is fixed to the said rocker 15, the pinion 12 is driven clockwise step by step.

The rocker 15, further, is provided with two outrigger-arms 23, on the ends of which movable pawls 25 are mounted. The latter are each biased by a spring 24, and co-act with an ink-ribbon feeding-wheel 26. The pawls 25 may be thrown into and out of engagement, in a manner known per se, during operation of the typewriter by virtue of a reversal through the ink-ribbon tension.

The ink-ribbon is raised by means of the fork 21 which guides the ink-ribbon past the central type-guide 9. The fork 27 is pivoted on a pin 31' to the lower portion 28 (Fig. 2) of the carriage, and is biased by a spring 29 (Fig. 6). When the rocker 15 is rocked, the fork 27 is rocked also in order to raise or lower the ink-ribbon.

As seen from Figs. 1 and 2, the spacing-key strap 30 is actuated from outside the keyboard, the said strap being pivoted at 31 in two lateral upright lugs of the bottom plate 3. The two linkages 32, which are articulated to the outer ends of the outswinging arms of the said strap 30, are each connected to a bell-crank 33, which latter is engaged in a longitudinal slot of the said pawl 25 through a nose and is fulcrumed in a slot of the ribbon-spool axle 34.

When the spacing-key strap 30 is actuated, the bell-crank 33 first is drawn outwardly in its bearing slot by the linkage 32, the pawl 25 (which is subjected to a slight spring tension) being disengaged from the wheel 26. The bell-crank 33 then is rocked on the axle pin 34, entraining the pawl 25 which further actuates the rocker 15 and thus releases the spacing-mechanism without actuating the ink-ribbon feed.

In the paper-feed device shown in Figs. 7-10, a pressure or engaging-roller 42 and a plurality of paper guide-rollers 43 are pivoted to the paper guide apron 41 so that the said rollers are parallel to each other. An axle pin 45 is borne for rotation in lateral lugs 44 of apron 41 and intermediate of the said rollers 42, 43, and is guided in slots 46 of the sidewall 47 of the upper carriage 48 of the typewriter. The said slots 46 are disposed radially with respect to the axle 49 of the platen 50 so that the pin 45 is movable toward and away from the latter. The axle pin 45, further, is mounted on each end in a slide 51. The slides 51 are each guided on a bearing-bush 53 by means of a slot 52, which bush is pressed into the sidewall 47. The two slides 51 thus are guided and displaceable on the bushes 53 along the sidewalls 47 of the upper carriage 48. A spring 54 which at one end is secured to carriage 48, engages the axle pin 45 in the middle thereof. The paper guide apron 41 is universally movable about the point of engagement of spring 54 so that the rollers 42, 43 over their entire lengths are pressed against the platen 50 under uniform pressure. Lateral bearing-portions of a paper-clamping strap 55, which portions are formed as levers and interconnected by a cross bar, are rotatably mounted on the sidewalls 48 of the upper carriage, and each is provided with a downwardly projecting dog 56 for the purpose of co-acting with the slides 51. When the lever 55 is swung upward from the position shown in Fig. 8 into that of Fig. 9, the introduced sheet of writing paper is only slipped underneath. The paper sheet or sheets are introduced between the guide apron 41 and the platen 50 in the fully open position of the clamping-device, as shown in Fig. 10. The strap 55 then is fully depressed so as to firmly clamp the sheet or sheets to the platen 50 which then is rotated to take the sheet or sheets along. In order to permit of slipping the latter underneath the cross-bar interconnecting the two levers 55, one of the latter is slightly raised from the position shown in Fig. 8 into that of Fig. 9, whereupon the said sheet or sheets are properly positioned, if required, and the lever 55 again depressed into the position shown in Fig. 8. It is to be noted that in the position of Fig. 9 the dog 56 does not yet operatively engage the slide 51 nor the apron 41 and the appurtenant clamping elements.

As shown in Fig. 11, the plane of segment 7, i. e. σ , is inclined at the angle α with respect to the base plane π_1 . A right-hand system of co-ordinates X, Y, Z is set up in the plane σ , wherein the positive X-axis is so aligned that it points to the left for the operator, and the positive Y-axis passes through base plane π_1 at point D₁ and coincides with the line of intersection of a plane of symmetry π_2^1 , which is parallel to the plane of elevation π_2 , and the plane σ .

The fulcra of the type-levers are situated in segment-plane σ ; when connecting these points by a line, we obtain a curve, the "pivotal axis" of the type-levers. Such latter axis is related to the system of axes X, Y in σ with the origin

in O (Fig. 11), and the following analytical expression is obtained therefor:

$$y=F(x) \quad (1)$$

Since the machine is built symmetrical to the plane of symmetry π^2 , the said pivotal axis in σ also comprises two curve-branches which are situated symmetrical to the ordinate-axis Y.

Expressing the curvature K in terms of the function $y=F(x)$, we obtain from the relation

$$y'=F'(x) = \tan \psi; \psi = \arctan y' \quad 10$$

$$K = \frac{1}{\rho} = \frac{\alpha \psi}{\alpha x} = \frac{y''}{[1+(y')^2]^{\frac{3}{2}}} \quad (2a)$$

Each type-lever has an extension reaching beyond its fulcrum. Such extension is pivoted at its end, as a crank of the size r , on a link of length l . The end of each link is articulated to the respective key-lever which is fulcrumed. When the key is depressed, the segment 1 is intersected by the type-lever in a normal plane, and each coupling point is situated in the respective plane which in σ is normal to the said pivotal axis of the type-levers. If we imagine that, when the key-levers are depressed, all the pivot points between links and key-levers are interconnected in their terminal position by a line, there results a spatial curve $\mathfrak{R}$ which is assumed to be continuous; the equations of its projections on the X-Y and the X-Z planes are considered to be predetermined.

$$\begin{aligned} y &= f(x) \\ z &= g(x) \end{aligned}$$

and the curve $\mathfrak{R}$ is considered to be produced as the intersection of the projecting cylinders which stand at right angles on these two planes.

In the following, the equations of the tangents for the terminal coupling points, which are disposed symmetrical to the plane of symmetry, namely the right-hand terminal point $P_i(x_i, y_i, z_i)$ and the left-hand terminal point $Q_k(x_k, y_k, z_k)$, as well as for the points nearest the plane of symmetry π^2 , namely $R_e(x_e, y_e, z_e)$ and $S_m(x_m, y_m, z_m)$ to the right and left respectively of the spatial curve $\mathfrak{R}$, shall be computed.

Designating the directional cosines of the tangent at point P_i of curve $\mathfrak{R}$ by $\bar{\alpha}i, \bar{\beta}i, \bar{\gamma}i$, and introducing any three numbers A, B, C which differ from the latter only by a common positive factor so that

$$A=k.\bar{\alpha}i; B=k.\bar{\beta}i; C=k.\bar{\gamma}i (k>0) \quad (4a, b, c)$$

may have any value, and at least one of the numbers A, B, C is different from zero, we have

$$\begin{aligned} \bar{\alpha}i &= \frac{A}{\{A^2+B^2+C^2\}^{\frac{1}{2}}}; \bar{\beta}i = \frac{B}{\{A^2+B^2+C^2\}^{\frac{1}{2}}} \\ \bar{\gamma}i &= \frac{C}{\{A^2+B^2+C^2\}^{\frac{1}{2}}} \quad (5a, b, c) \end{aligned}$$

For the numbers A, B, C we then may write:

$$\begin{aligned} A &= 1; B = \frac{\alpha f(x)}{\alpha x} \Big|_{x=x_i} = f'(x_i) \\ C &= \frac{\alpha g(x)}{\alpha x} \Big|_{x=x_i} = g'(x_i) \quad (6a, b, c) \end{aligned}$$

and we obtain for the equation of the tangent at the point $P_i(x_i, y_i, z_i)$ the parameter expression

$$x=x_i+At; y=y_i+Bt; z=z_i+Ct \quad (7a, b, c) \quad 75$$

In the same way we obtain, with

$$A'=1; B' = \frac{\alpha f(x)}{\alpha x} \Big|_{x=x_k} = f'(x_k)$$

$$C' = \frac{\alpha g(x)}{\alpha x} \Big|_{x=x_k} = g'(x_k) \quad (8a, b, c)$$

the equation of the tangent at point $Q_k(x_k, y_k, z_k)$,

$$x=x_k+A't; y=y_k+B't; z=z_k+C't \quad (9a, b, c)$$

Since the coefficient determinant of the four equations of the two straight lines (7) and (8), written in the form $ax+by+cz+d=0$ identically disappears, the said lines intersect. Eliminating the parameter t from the Equations 7 and 9, one first obtains from the two equations

$$x-x_i = \frac{1}{f'(x_i)}(y-y_i)$$

$$x-x_k = \frac{1}{f'(x_k)}(y-y_k) \quad (10a, b)$$

the co-ordinates of the point of intersection P_0

$$x_0 = \frac{y_i - y_k + x_k f'(x_k) - x_i f'(x_i)}{f'(x_k) - f'(x_i)} \quad (11a)$$

and

$$y_0 = \frac{y_i f'(x_k) - y_k f'(x_i) + (x_k - y_i) f(x_i) f'(x_k)}{f'(x_k) - f'(x_i)} \quad (11b)$$

The co-ordinate z_0 of the point of intersection P_0 is obtained from the solution of the equations

$$x-x_i = \frac{z-z_i}{g'(x_i)} \quad (12a)$$

$$x-x_k = \frac{z-z_k}{g'(x_k)} \quad (12b)$$

as

$$z_0 = \frac{g'(x_i) z_k - g'(x_k) z_i + (x_i - x_k) g'(x_i) g(x_k)}{g'(x_i) - g'(x_k)} \quad (13)$$

For the equations of the tangents at the points $R_e(x_e, y_e, z_e)$ and $S_m(x_m, y_m, z_m)$ we first obtain — with the values $\bar{A}=1$, $\bar{B}=f'(x_e)$; $\bar{C}=g'(x_e)$ for the equations of the tangent at point R_e , and with the values $\bar{A}'=1$; $\bar{B}'=f'(x_m)$, $\bar{C}'=g'(x_m)$ for the equations of the tangent at point S_m — with the aid of a parameter t

$$x=x_e+\bar{A}t; y=y_e+\bar{B}t; z=z_e+\bar{C}t \quad (14a, b, c)$$

$$x=x_m+\bar{A}'t; y=y_m+\bar{B}'t; z=z_m+\bar{C}'t \quad (15a, b, c)$$

Due to the linear dependency or, respectively, the identical disappearance of the coefficient-determinant of the four equations for the two tangents — which are expressed in the form $ax+by+cz+d=0$ — the said tangents intersect, and we obtain (for determining the co-ordinates x_0', y_0' of their point of intersection in P_0') the two equations, as above

$$x-x_i = \frac{1}{f'(x_i)}(y-y_e)$$

$$x-x_m = \frac{1}{f'(x_m)}(y-y_m) \quad (16a, b)$$

The solution of these latter equations furnishes

$$x_0' = \frac{y_e - y_m + z_m f'(x_m) - x_e f'(x_l)}{f'(x_m) - f'(x_e)} \quad (17a)$$

$$y_0' = \frac{y_e f'(x_m) - y_m f'(x_e) + (x_m - x_e) f(x_e) f'(x_m)}{f'(x_m) - f'(x_e)} \quad (17b)$$

After eliminating the parameter t , the following two equations are obtained from the Equations 14a, c and 15a, c for computing the co-ordinate z_0' of point P_0' :

$$x - xe = \frac{z - ze}{g'(xe)}; x - zm = \frac{z - zm}{g'(xm)} \quad (18a, b)$$

From the Equations 18a, b we obtain the following value for the co-ordinate z_0' :

$$z_0' = \frac{g'(xe)zm - g'(xm)ze + (xe - xm)g'(xe)g'(xm)}{g'(xe) - g'(xm)} \quad (18c)$$

When drawing a straight line $f = \omega + bt$ (19) through the two points of intersection P_0 and P_0' of the two pairs of tangents—for the purpose of characterising the kinematics—the said line will be situated in the plane of symmetry π_2^1 owing to the symmetry of the appurtenant points of tangent P_i , Q_k , and R_e , S_m , since their points of intersection have identical abscissa values.

The said straight line (19) includes the following angle with the plane of the segment

$$\tan \sigma = \frac{z_0 - z_0'}{y_0 - y_0} \quad (20)$$

whereby the values entering into Equation 20 are to be taken from the Equations 11b, 13, 17b and 18c.

Expressing the co-ordinates of any point B_i of the coupling link (5 in Figs. 1, 2 and 4) by the kinematic angles ai , βi with respect to the plane σ (Fig. 12), and the normal ni , down to its point of intersection with the ordinate-axis Y in σ , by the derivation of the "pivotal axis" $y = F(x)$ and the co-ordinate $\bar{x}_i$, $\bar{y}_i$ of the point of intersection of the said line ni with the curve $y = F(x)$, we put

$$yi = (ni + r \cos ai + l \cos \beta i) \sin \varphi i + mi \quad (21a)$$

$$xi = (ni + r \cos ai + l \cos \beta i) \cos \varphi i \quad (21b)$$

$$zi = r \sin ai + l \sin \beta i \quad (21c)$$

wherein

$$ni = \frac{\bar{x}_i}{\cos \varphi i} = \bar{x}_i \frac{\sqrt{1 + F'^2(\bar{x}_i)}}{F'(\bar{x}_i)} \quad (22)$$

$$mi = \bar{y}_i - \frac{\bar{x}_i}{\operatorname{ctg} \varphi i} = \bar{y}_i + \bar{x}_i \frac{1}{F'(\bar{x}_i)} \quad (23)$$

In these latter expressions, r denotes the crank radius, i. e. the type-lever extension which projects beyond the fulcrum up to the pivot of the link 5. The letter l denotes the length of the latter in the Equations 21. The co-ordinates xi , yi belong to that point to which the normal to the "pivotal axis" of the function $y = F(x)$ points. The length cut off the ordinate-axis Y by the normal ni , is designated by mi .

What we claim and desire to secure by Letters Patent is:

1. A typewriter comprising a plurality of type-levers, an inclined segment block having slots for guiding the type-levers, a plurality of key-levers arranged in four rows and each having an arm carrying a key and an outswinging arm, a plurality of links for directly connecting each outswinging arm of a key-lever without intermediate lever to the respective type-lever, and bearing means providing a guide slot and a fulcrum for each key lever, the fulcrum being arranged in four parallel rows and situated in a common horizontal plane, and the guide slots

being tilted with respect to the vertical plane, the angle of inclination of successive slots gradually increasing from the center towards both sides of the typewriter whereby successive key-levers are caused to swing in planes of gradually increased inclination towards the sides of the typewriter, the outswinging key-lever arms being bent off at a gradually increasing rate in the direction of the type-lever guiding slots from the center of the typewriter toward the two sides thereof, the different angles of bend of the outswinging key-lever arms depending on the inclination of the said segment block, the position of the respective planes of the said type-lever guiding slots, and the position of the respective planes of swing of the appurtenant key-levers, such that the ends of the outswinging key-lever arms move in the respective planes of the appurtenant type-lever guiding slots.

2. A typewriter comprising a plurality of type-levers, an inclined segment block having slots for guiding the type-levers, a plurality of key-levers arranged in four rows and each having an arm carrying a key and an outswinging arm, a plurality of links for directly connecting each outswinging arm of a key-lever without intermediate lever to the respective type lever, the said type-levers from the center of the typewriter toward the two sides being of increasing length, a wire arranged in the segment block for bearing the type-levers and curved according to the increasing length of the type-levers, and bearing means providing a guide slot and a fulcrum for each key-lever, the fulcrum being arranged in four parallel rows and situated in a common horizontal plane and the guide slots being tilted with respect to the vertical plane, the angle of inclination of successive slots gradually increasing from the center towards both sides of the typewriter whereby successive key-levers are caused to swing in planes of gradually increased inclination towards the sides of the typewriter, and the outswinging key-lever arms being bent off at a gradually increasing rate in the direction of the type-lever guiding slots from the center of the machine toward the two sides thereof, the different angles of bend of the outswinging key-lever arms depending on the inclination of the said segment block, the position of the respective planes of the said type-lever guiding slots, and the position of the respective planes of swing of the appurtenant key-levers, such that the ends of the outswinging key-lever arms move in the respective planes of the appurtenant type-lever guiding slots.
